UNITED STATES PATENT OFFICE.

CHARLES FREDERICK BROOKER, OF ANSONIA, CONNECTICUT, ASSIGNOR TO
THE COE BRASS MANUFACTURING COMPANY, OF CONNECTICUT.

MACHINE FOR ROLLING METAL FORMS.

SPECIFICATION forming part of Letters Patent No. 694,722, dated March 4, 1902.

Application filed June 16, 1899. Serial No. 720,869. (No model.)

To all whom it may concern:

Be it known that I, CHARLES FREDERICK BROOKER, a citizen of the United States, residing at Ansonia, State of Connecticut, have ⁵ invented a Machine for Rolling Metal Forms, of which the following is a specification.

My invention relates to a machine constructed to roll copper forms; and it consists of a special arrangement of edging-rolls, facing-rolls, guides, clutches, and other operating mechanism by means of which a strip of copper or other metal may be first straightened and subsequently rolled to a variety of shapes and finally delivered from the machine in a ¹⁵ finished state.

The object of my invention is a machine by which bodies of copper may be given definite shapes by rolling instead of drawing, as has heretofore been the practice, and thereby materially decrease the cost of production of ²⁰ such shapes.

In the drawings similar numerals indicate like parts in the several figures.

Figure 1 is a front view of the machine with ²⁵ the small directing-rolls shown in Fig. 2 removed. Fig. 2 is an end view and vertical section through the supporting-bracket and one of the adjusting-screws for the housings which carry the edging-rolls and also shows ³⁰ the main frame for the facing-rolls broken away at the bottom in order to illustrate the position of the adjusting-screws for the lower of the facing-rolls. Fig. 3 is a front view of the facing-rolls with their supporting-frame, ³⁵ with one side of the supporting-frame and also the universal bearings and driving-shafts shown in vertical section. Fig. 4 is a side view of the guides in front and behind the facing-rolls, with the facing-rolls in vertical ⁴⁰ section. Fig. 5 is a front view of the guide located between the edging-rolls and the facing-rolls.

In the drawings, 5 indicates the supporting-frame for the facing-rolls. The frame consists of a base 6 and uprights 7. The uprights 7 are slotted vertically, as shown at 8, Fig. 2, and in these slots are located vertically-adjustable bearings 9 and 10. The upper bearings 9 are carried by the rods 11 and ⁴⁵ yoke 12 and are vertically adjustable in the frame by means of the screws 13. The lower

bearings 10 are supported on and made adjustable by means of the screws 14.

Secured to the ends of the screws 13 and 14 are the concave bearing-seats 15, and carried in these bearing-seats are the plano-convex bearings 16. These bearings conform on their plain surface to the contracted portion 17 of the facing-rolls 18. In the drawings, Figs. 1 and 3, the facing-rolls are shown as ⁵⁵ 60 angularly disposed as regards each other—i. e., in the position which they would be arranged to roll a V-shaped copper form. By means of the adjusting-screws 13 and 14 the facing-rolls may have their axes adjusted as ⁶⁵ regards each other—that is, the axes of the rolls may be parallel or the angular inclination of the axes altered at will. It will be observed that by reason of the adjusting-screws ⁷⁰ 13 and 14 both of the rolls may be adjusted and not one roll, as is usually the case. The ends 19 of the rolls 18 are hexagonal in shape and connected through couplings 20, also hexagonal on their interior, to the hexagonal driving-shaft 21. The particular shape given ⁷⁵ to these parts is not material.

Located on the outer sides of the uprights ⁷ are the thrust-plates 22, which serve to prevent the lateral displacement of the vertically-adjustable bearing-seats 15, but do not interfere with the rolling of the plano-convex bearings 16.

Located on the front of the machine and in front of the facing-rolls and formed as a part of the machine by casting or connected there- ⁸⁵ to in any suitable manner, as by means of bolts, is a bracket-support 23. The top of this support is cut away to form a dovetailed longitudinal slot 24 and concave longitudinal opening 25.

Located on the top of the bracket-support and movable thereon, are the housings 26, for the edging-rolls. The base of the housings is provided with a dove shaped projection 27, which takes in the dove-tailed slot 24 in the ⁹⁵ bracket 23, and the housings are also provided with depending portions 28, each having a threaded opening and in which are located the threaded shafts 29, 29^a. These shafts have corresponding horizontal axes and act in connection with the threaded opening of the housings to give the housings longitudinal ¹⁰⁰

motion to and from each other along the top of the bracket-support 23. The upper portion of the housings 26 are formed as bearings 30, and located and supported in these 5 bearings is a slotted shaft 31. Located upon this shaft are the beveled gears 32. These gears are loose upon the shaft, and therefore capable of longitudinal motion on the shaft, and receive motion from the shaft through 10 the instrumentality of keys 33. The gears 32 mesh with the gears 34, which are carried in the bearings 35. Connected to the gears 34 are the short hexagonal shafts 36.

15 Mounted on the shafts 37, which have their bearings in the bottom of the housings, are the edging-rolls 38. These rolls may be given any surface contour desired. Those shown in the drawings have two diameters, the greater diameter being at the bottom.

20 Mounted on the shafts 36 are the slotted clutches 39, having hexagonal openings which correspond to the shape of the shafts 36 and 37. Vertical movement is imparted to these clutches by means of the levers 40, which are pivoted at 41 to the housings 26. The inner 25 ends of the clutch-levers are forked, as at 42, and partially surround the clutches, to which each is loosely connected through pins 43, which take in the slots 44 of the clutches 39.

30 By means of the levers 40 the edging-rolls 38 can be thrown into and out of operation, as desired.

35 My object in providing the edging-rolls with independent clutches is for the purpose of permitting the edging-rolls to be operated separately or conjointly. By operating the rolls separately—that is, allowing one roll to run loose and the other to be driven positively—the strip passing the machine may be 40 straightened before it is carried between the facing-rolls. Further, by mounting the edging-rolls on independent shafts separate from the driving-shafts I am able to readily substitute edging-rolls of different surface con- 45 tour.

45, 46, and 47 represent gears intermediate of the main driving-shaft and the shaft 31. The arrangement of these gears is such that the speed of the edging and facing rolls will 50 be the same.

55 Mounted between the edging-rolls and the facing-rolls is the front guide 50, and located behind the facing-rolls is the back guide 51. These guides consist of pairs of oppositely disposed guide-boxes 52. The shape given to these boxes is best shown in Fig. 5—that is, the boxes project at the top and bottom toward each other and have a cavity at or about their centers. The object of giving them this 60 shape is to direct the material passing through the machine along a horizontal plane and prevent the material curling upward. I do not limit myself to the particular shape given to these guide-boxes, as it may be varied without departing from the intent of my invention.

The guide-boxes 52 are mounted upon the horizontal plate 53, which is supported by the vertical side frames 54, secured to the uprights 7 of the machine. The guide-boxes 52 70 are longitudinally adjustable upon the supporting-plate 53 and to or from the facing-rolls 18 by means of the screws 55, and they are also adjustable relatively to each other—i. e., transversely of the plate 53 by means of 75 the screws 56—so that the distance between them may be altered.

The guide-boxes 52 of the guide 50 project between the rolls 18, but are not carried past the vertical axis of the rolls, whereas the 80 guide-boxes of the guide 51 project past the vertical axis. This is the only difference of construction between the guides 50 and 51, and this difference in construction is for the purpose of preventing a strip when passing 85 the rolls from following the curvature of the rolls and turning upward. The shape of the guide-boxes projecting through the rolls prevents this.

90 Located in front of the edging-rolls 38 and supported upon the bracket 23 is a pair of vertically-disposed directing-rolls 57 and back of them a pair of horizontally-disposed adjustable directing-rolls 58. These rolls serve to guide the strip toward the edging-rolls. 95

The operation of my device is as follows: The strip to be straightened and rolled into shape is introduced through the directing-rolls 57 and 58 until it is caught between the oppositely-disposed edging-rolls 38. These 100 rolls determine the width and shape of the edges of the strip. After leaving the edging-rolls it passes into the guide 50 and thence through the facing-rolls, which determine the general cross-section of the strip, and thence 105 through the rear guide 51 and out of the machine. It will be observed that the path of movement of the strip through the machine from the time it enters the directing-rolls 57 until it leaves the machine is along a straight 110 horizontal plane. The result of the action of the machine upon the strip is a copper body of definite and predetermined shape, straight and with finished edges. As has been explained, the contour of the body may be 115 changed by altering the relation of the axes of the facing-rolls and the contour of the edging-rolls, and bodies of different width may also be obtained by changing the distance between the pairs of facing-rolls and 120 pairs of edging-rolls or of the one relatively to the other.

Having thus described my invention, I claim—

1. In a machine for rolling metal forms, the 125 combination with a pair of facing-rolls, a pair of edging-rolls, and means for throwing either one of the edging-rolls into and out of operation.

2. In a machine for rolling metal forms, the 130 combination of a pair of facing-rolls, a pair of edging-rolls having contoured faces and ad-

- justable as regards each other, and means for throwing either one of the edging-rolls into and out of operation.
3. In a machine for rolling metal forms, the combination of a pair of edging-rolls, a pair of housings adjustable relative to each other, mechanism for adjusting the housings, mechanism for positively driving the edging-rolls carried on and moving with said housings, and mechanism interposed between the driving mechanism and the edging-rolls, whereby the edging-rolls may each be independently thrown into and out of operation.
4. In a machine for rolling metal forms, the combination of a pair of facing-rolls, means for altering the angular inclination of both of said rolls relative to each other, a pair of edging-rolls, and means for simultaneously moving said edging-rolls to or from each other.
5. In a machine for rolling metal forms, the combination of a supporting-frame, a pair of facing-rolls, universal bearings for each of said rolls, means for independently adjusting said bearings, whereby the angular inclination of the rolls as regards each other may be altered, a pair of edging-rolls, and means for simultaneously adjusting the distance between the edging-rolls.
6. In a machine for rolling metal forms, the combination with a frame provided with a bracket-support on the front and having a longitudinal slot in the upper surface of said support, a pair of housings having depending portions provided with threaded openings, which portions take in the slot of the bracket-support, a pair of edging-rolls mounted in said housings, and a shaft having its bearings in said bracket-support and provided with oppositely-disposed screw-threads which respectively coat with the threaded openings in the depending portions of the housings.
7. In a machine for rolling metal forms, the combination of a main frame provided with a bracket-support on the front and having a longitudinal slot in the upper surface of said support, a pair of housings having depending portions provided with threaded openings, which portions take in the slot of the bracket-support, means for adjusting the distance between said housings, a pair of edging-rolls, vertical driving-shafts for such edging-rolls carried in said housings but separate from said rolls, a horizontal driving-shaft carried in said housings and adapted to transmit motion to the vertical shafts, and clutch mechanism located between each vertical shaft and each vertical roll.
8. In a machine for rolling metal forms, the combination of a pair of vertical guide-rolls, a pair of horizontal guide-rolls, a pair of edging-rolls, a pair of facing-rolls, a guide between the edging-rolls and the facing-rolls, and a guide to the rear of the facing-rolls, the axis of the opening of said rolls and guides located in the same horizontal plane.
9. In a machine for rolling metal forms, the combination of a pair of housings, adjustable as regards each other, a slotted driving-shaft carried in said housings, loose gears mounted on said driving-shaft and keyed thereto, a pair of gears carried in said housings and meshing with said first-named gears, shafts depending from said second-named gears, a pair of edging-rolls mounted on shafts whose axes correspond to the axes of the shafts connected to the second-named gears, independent clutch mechanism introduced between said shafts, and levers under the control of the operator for manipulating said clutch mechanism.
10. In a machine for rolling metal forms, the combination with the adjustable housings, provided with the bearings 30, the slotted shaft 31, loose beveled gears 32, gears 34, shafts 36, edging-rolls 38, clutches 39, and independent levers 40 for manipulating said clutches.
11. In a machine for rolling metal forms, the combination of a slotted frame, thrust-plates secured to said frame, a pair of facing-rolls, bearings for said facing-rolls, and means for vertically adjusting said bearings.
12. In a machine for rolling metal forms, the combination of a slotted frame, thrust-plates on said frame, a pair of facing-rolls, a pair of suspended bearings for the upper facing-roll, means for vertically adjusting said bearings, a pair of bearings for the lower facing-roll, and means for vertically adjusting said bearings.
13. In a machine for rolling metal forms, the combination with the edging-rolls and guides, of a pair of facing-rolls, and means for altering the angular inclination of the rolls relative to each other without altering the horizontal plane through which the material passing these rolls is obliged to travel.
- In testimony whereof I affix my signature in the presence of two witnesses.
